ABSTRACT

An electrically conductive sheet of flexible material includes conductive particles and channel-shaped electrodes are provided on opposite ends and are connected by lead wires to a power source. A flexible insulating envelope is bonded to and protects the conductive sheet. Holes may be provided in the conductive sheet to facilitate bonding between the protective cover and the conductive sheet. The conductive particles may be carbon and the sheet may be formed from fibrous material or rubber. The protective sheet may be molded from plastic or rubber having a very low carbon content.

ELECTRICAL HEATING PAD

Portable heaters are commonly used in and out of doors. Inside they may be used for a desk top warmer, desk foot warmer, foot stool warmer or for heating pads. Winter conditions outside make them desirable for windshield deicers, seat warmers and car and dog house warmers.

One of the most important uses is for maintaining a battery at the optimum temperature level to maximize the battery power available for starting engines.

The heating pad of this invention contains no wires or ribbons and will not develop hot spots and burn out. There is basically nothing to break and can become partially damaged and still function. The electrical properties remain unchanged by the unit being exposed to dampness and then redrying. Further, repeated flexing has little effect on the electrical properties. The conductive element has uniform conductivity from point to point over the element regardless of the direction of current flow. Also, very important is the fact that the heater unit can be produced more inexpensively than a conventional wire-wound heater unit.

The heater unit of this invention includes a sheet of conductive material which is highly flexible and has channel-shaped electrodes at opposite ends connected to lead lines adapted to be connected to a power source.

This invention consists in the construction, arrangements and combination of the various parts of the device, whereby the objects contemplated are attained as hereinafter more fully set forth, specifically pointed out in the claims, and illustrated in the accompanying drawings in which:

FIG. 1 is a perspective view of the electrical heating pad of this invention; and

FIG. 2 is an enlarged fragmentary perspective view thereof.

The heating pad of this invention is referred to generally in FIG. 1 by the reference numeral 10. The heating pad includes a flexible electrically conductive sheet 12. Suitable materials include rubber having carbon particles impregnated therein in sufficient quantities to make the sheet electrically conductive. Thermosheet produced by Armstrong Cork Company, Lancaster, Pennsylvania, is also acceptable. A channel-shaped electrode 14 is secured to the opposite ends of the sheet 12 and bonded in place by any suitable means such as the staples 16, seen in FIG. 2. The electrodes 14 are preferably brass.

An electrical lead line 16 includes one line 18 connected to one electrode while the other line 20 is con-

nected to the opposite electrode 14. A rivet and solder connection 22 is used for connecting the lead line wires to the electrodes.

The electrically conductive sheet 12 is enclosed in an envelope 24 of insulating material such as rubber having no carbon or very little carbon. A flexible plastic may also be used. The conductive sheet 12 is completely sealed within the protective envelope 24 by a molding or vulcanizing process. Openings 26 are provided in the sheet 12 to further facilitate the bonding of the envelope material to the conductive resistance sheet 12.

It is seen in FIG. 2 that the electrodes 14 are inwardly spaced from the outer adjacent edges of the envelope 24 and thus provide extra protection at the ends of the heating pad and in particular provide flexible support for the electrical lead line 16 to minimize stress and strain at the electrodes 14.

It is seen that the use of synthetic natural rubber or plastic in the envelope 24 provides resistance and protection against the action of solvents, acids, and moisture making the heating pad very suitable for industrial applications including the warming of batteries. It is further seen that there is essentially nothing to break in this heating pad as there are no wires or ribbons to break. Further, the carbon impregnated resistance sheet of the battery heater of this invention can be produced more economically than a wound-wire battery heater.

I claim:

1. An electrical heating pad comprising, an electrically conductive sheet of flexible material having electrically conductive particles uniformly disposed throughout said sheet, an electrode secured to opposite ends of said sheet, said electrodes being channel shaped and the opposite edges of said conductive sheet are received in said channel-shaped electrodes, an electrical lead wire connected to each of said electrodes, and an envelope of electrically insulative flexible material molded onto and enclosing said sheet, said envelope having a size larger than said sheet so that said sheet is completely enclosed therein, said conductive sheet having a plurality of openings formed therein which receive the flexible material of said envelope to bond the envelope to said conductive sheet said channel-shaped electrodes and said conductive sheet being stapled together.
